This

UNITED STATES PATENT OFFICE.

ARTHUR SCHOSHUSEN, OF CHICAGO, ILLINOIS.

LACING.

No. 805,385.

Specification of Letters Patent.

Patented Nov. 21, 1905.

Application filed February 25, 1905. Serial No. 247,346.

To all whom it may concern:

Be it known that I, ARTHUR SCHOSHUSEN, a citizen of the United States, residing at Chicago, in the county of Cook and State of Illinois, have invented certain new and useful Improvements in Lacings, of which the following is a specification.

My invention relates to lacings such as are employed for the fastenings of shoes, corsets, &c.; and its object is to provide a new and improved lacing tip or stiffener of simple and inexpensive construction and increased durability as compared with tips heretofore used for similar purposes. In one form my invention provides a tip having an exposed metallic point, while in another form it is designed to be entirely incased and concealed in the end of the lacing.

In the accompanying drawings I have illustrated my improved tip and the manner of applying the same to the end of a lacing in connection with both a tubular lacing and a lacing of the wide single-strip style, and, referring thereto—

- 25 Figure 1 is a plan view of the sheet-metal blank from which the tip or stiffener is formed. Fig. 2 shows the shank of the tip inserted in the end of a tubular lacing. Fig. 3 illustrates the next two steps in the operation of forming up the tip, consisting in folding over the side wings and bending the head of the blank down against the cloth covering the neck. Fig. 4 illustrates the next succeeding step, which consists in folding the side portions of 35 the head inwardly upon the fabric of the lacing. Fig. 5 illustrates the completed tip formed by bending together the longitudinal halves of the partly-finished tip shown in Fig. 4. Fig. 6 is a cross-sectional view of the 40 partly-finished tip on the line 6 6 of Fig. 4. Fig. 7 is a similar view on the line 7 7 of Fig. 4. Fig. 8 is an end view of the finished tip shown in Fig. 5. Fig. 9 is a cross-sectional view of the finished tip on the line 9 9 of Fig. 45 5. Fig. 10 is a similar view on the line 10 10 of Fig. 5. Fig. 11 shows the blank of Fig. 1 applied to a wide single-strip lacing. Fig. 12 illustrates the next step in the operation, consisting of folding the edge portions of the 50 lacing over the wings of the blank. Fig. 13 illustrates the condition of the lacing at the conclusion of the next three steps in the operation, which consist in folding inwardly the wings of the body and the overlying portions 55 of the lacing, turning down the head portion, and folding inwardly the sides of said head

portion. Fig. 14 illustrates the completed tip formed by bending together the longitudinal halves of the partly-finished tip shown in Fig. 13. Fig. 15 shows the form of blank used in 60 making an inclosed or covered tip. Fig. 16 shows the latter inserted in the end of a tubular lacing. Fig. 17 illustrates the next two steps of the operation, consisting in folding down the upper end portion of the lacing over 65 the upper end of the blank and then bending inwardly over the same the side portions of the blank. Fig. 18 illustrates the completed tip formed by bending together the longitudinal halves of the partly-finished tip shown in 70 Fig. 17. Fig. 19 shows the blank of Fig. 15 applied to a wide single-strip lacing preliminary to its incorporation therein. Fig. 20 shows the upper end of the lacing bent down over the upper end of the blank and the sides 75 of the blank and overlying lacing folded inwardly over the bent-down upper end portion, and Fig. 21 shows the finished tip formed by bending together the longitudinal halves of the partly-finished tip shown in Fig. 20. 80

Referring first to Figs. 1 to 10, inclusive, A designates a tubular lacing, and B designates as an entirety a thin sheet-metal blank from which my improved tip having an exposed metallic end is formed. This blank comprises 85 a body portion b, a neck b', a head b'', side wings b³ on said head, and side wings b⁴ on said body. In applying the tip the body portion b, with its integral wings b⁴ and the neck b', is inserted in the open end of the tubular 90 lacing A to the extent indicated in Fig. 2. The body b, with the side wings b⁴, is of somewhat greater width than the contracted width of the lacing, thereby causing the latter to bulge somewhat when the blank is inserted, 95 as shown in Fig. 2. The next step consists in folding the wings b⁴, with those portions of the lacing overlying the same, over around the main body portion b, as clearly indicated in Fig. 3, after which the head b'', with the wings 100 b³, is bent back upon a transverse line across the upper end of the neck b' to the position shown in Fig. 4, wherein the head lies over and against the lacing which incloses the neck b', with the wings b³ projecting from either 105 side thereof. This done, the wings b³ are next bent inwardly toward each other, so as to overlie and compress the edges of the lacing adjacent to its end, as shown in Fig. 4, after which the blank thus folded and bent, with 110 the end portion of the lacing engaged thereby, is doubled or folded together along the lon-

gitudinal median line of the blank, producing the finished tip shown in Figs. 5 and 8, wherein it will be observed that all parts of the blank excepting the head and its wings are 5 completely incased in the lacing and concealed from view. The stiffener is secured in the lacing primarily by reason of the clamping of the lacing between the folded-over wings b^4 and the body portion b , said wings being 10 pressed hard against the body and preventing the pulling out of the stiffener. Said wings b^3 of the head folded over upon the upper end portion of the lacing also contribute in a less degree to the anchorage of the stiffener in 15 the lacing. The final doubling together of the longitudinal halves of the lacing and incorporated stiffener to the finished form shown in Fig. 5 is simply to reduce the transverse dimensions of the tip and give it a neat, pointed, and finished appearance; but this final 20 folding is not at all essential for the purpose of clamping the lacing in the bends or folds of the metallic stiffener. The enlarged cross-sectional views, Figs. 6 to 10, inclusive, all 25 serve to illustrate how the fabric of the lacing is clamped and held between the wings and the body portion and head of the stiffener.

Where the tip is applied to a wide single-strip lacing, as illustrated in Figs. 11 to 14, 30 inclusive, substantially the same operations as to folding and bending of the tip are carried out as hereinabove set forth. In this case, as shown in Fig. 11, the body, neck, and wing portions of the blank are laid longitudinally and centrally upon the end of the lacing A' , the edges of the lacing being then folded inwardly over the body, wings, and around the neck, as shown in Fig. 12. The head with its wings is then bent backwardly 35 to overlie the end portion of the fabric covering the neck, after which the covered wings of the body portion are folded inwardly to clamp the edges of the folded end of the fabric against the intermediate body portion, 40 and the wings b^3 of the head are then folded inwardly, producing the result shown in Fig. 13, or the wings of the body may first be folded inwardly and the head then bent down and its wings inwardly turned, as found most 45 convenient or expedient. The tip in the condition shown in Fig. 13 is then folded together along its longitudinal median line, producing the finished tip shown in Fig. 14, which 50 closely resembles in appearance the tubular lacing-tip shown in Fig. 5.

The principle of my invention is capable of being carried out in both tubular and single-strip lacing-tips, wherein the metallic stiffener is completely incorporated in the end 55 of the lacing and concealed from view. In this form of the invention I modify the form of the metallic blank by omitting the head and neck portions and preferably make the body portion of increased length as compared 60 with the body portion of the headed blank.

Referring to Figs. 15 to 18, inclusive, B' , Fig. 15, may designate as an entirety the blank form of stiffener, consisting of the intermediate body portion b^5 and the longitudinal side wings b^6 , extending the full length 70 thereof, the lines of fold between the body and wings being indicated by the parallel longitudinal dotted lines b^7 . In applying this stiffener to a tubular lacing it is simply inserted into the end of said lacing far enough 75 to leave the end flap or fold on the latter, (designated by a .) In the first operation of forming the tip this flap a is folded down against the fabric, overlying the upper end of the blank on either side of the latter, after which 80 the wings b^6 , with the marginal portions of the fabric covering them, are folded inwardly, so as to overlie and fasten down the flap a , as clearly shown in Fig. 17. That done, the final 85 and finishing operation consists, as already described in connection with Figs. 5 and 14, in simply bending together the longitudinal halves along the longitudinal median line of the blank, producing the completely incased and inclosed tip shown in Fig. 18. In the 90 application of this form of stiffener to the wide single-strip lacing substantially the same operations are carried out, the blank being first laid directly upon the end of the lacing, as shown in Fig. 19, the end flap a' of the lacing being then folded down across the upper 95 end of the blank, the edge portions of the lacing being then folded over the wings b^6 , and the latter, thus covered, being folded inwardly to clamp said edge portions of the lacing against the body portion of the stiffener, all as shown in Fig. 20, after which the partly-finished tip is folded together along its longitudinal median line, producing the finished 100 article shown in Fig. 21.

It will be observed as constituting a feature common to both forms of stiffener-blanks herein described and to both applications of the same that the metallic stiffener is anchored and secured in and to the end of the lacing through the provision of the longitudinally-extending wings on the main body portion of the stiffener, which are folded over upon said body portion in such a way as to clamp therebetween a portion of the lacing, the final 110 fold being, as already suggested, simply for the purpose of reducing the transverse dimensions of the tip and giving the same a neat and finished appearance. In the manufacture 115 of my improved lacing-tip the only operations required are bending and folding operations, which are simple and easily and cheaply performed as compared with the more usual operations of rolling and curling, so as to produce a substantially round tip. Furthermore, 120 I have found by practical tests that the grip of the fabric upon the metallic stiffener is stronger and more secure where said parts are folded and compressed together than where 125 they are simply rolled up together, so as to 130

hold the fabric between meeting or overlapping longitudinal edges of the stiffener.

I claim—

1. The combination with a lacing, of a metallic stiffener therefor of less width than said lacing, said stiffener having a body portion and side wings over which latter the edge portions of the lacing are folded, said wings and their covering edge portions of the lacing being folded over upon said body portion, and the longitudinal halves of the stiffener being folded together flat on the longitudinal median line, substantially as described.
2. The combination with a tubular lacing, of a metallic stiffener therefor having a body portion with side wings inserted into the end of said tubular lacing, said wings with the side portions of the lacing covering the same being folded over upon the fabric covering, said body portion thereby clamping the lacing between said wings and body portion, and the longitudinal halves of the stiffener being folded together flat on the longitudinal median line, substantially as described.
3. The combination with a lacing, of a metallic stiffener therefor having a head portion with side wings, an intermediate neck portion, and a body portion with side wings, the side wings of said body portion being folded over

upon the latter and clamping the edge portions of the lacing between said wings and body portion, said head portion being bent back over the fabric covering the neck with its side wings folded inwardly over the latter, and the longitudinal halves of the stiffener thus formed being folded together flat on the longitudinal median line, substantially as described.

4. The combination with a tubular lacing, of a metallic stiffener therefor having a body portion with side wings and an intermediate neck portion inserted into the end of the lacing, and a head portion with side wings projecting from the end of said lacing, the side wings of said body portion being folded over upon the latter and clamping the edge portions of the lacing between said wings and body portion, said head portion being bent back over the fabric covering the neck with its side wings folded inwardly over the latter, and the longitudinal halves of the stiffener thus formed being folded together flat on the longitudinal median line, substantially as described.

ARTHUR SCHOSHUSEN.
